His Attorney.

UNITED STATES PATENT OFFICE.

ANTON J. NEMEC, OF CLEVELAND, OHIO, ASSIGNOR TO ELECTRIC VACUUM CLEANER COMPANY, INC., OF CLEVELAND, OHIO, A CORPORATION OF NEW YORK.

JACKET FOR MOLDS.

Application filed September 13, 1923. Serial No. 662,429.

In the art of casting, especially of small pieces, it is customary to use what is termed "a snap flask" in which to form sand molds. Such flasks are commonly made in two parts which enclose the mold on all four sides and are open at the top and bottom. These parts are united, usually at two corners, by some sort of a quick-acting snap catch.

10 After the sand mold is formed in the usual manner it is placed on a suitable support called the "run-board" preparatory to receiving the molten metal and the flask is removed, thus leaving the mold unsupported except on the bottom. Molds formed in this manner are liable to be injured from one cause or another and may give way during the pouring operation.

My invention is directed to a jacket for holding a sand mold after the snap flask is removed and prior to and during the pouring operation.

For a consideration of what I believe to be novel and my invention, attention is directed to the accompanying description and claims appended thereto.

In the accompanying drawing Fig. 1 is a view in side elevation of a snap-flask; Fig. 2 is a view in side elevation of a sand mold after the flask is removed; Fig. 3 is a plan view of my improved molding jacket; Fig. 4 is a view in side elevation of one of the members of the jacket; Fig. 5 is a view in side elevation and partly in section illustrating the jacket as it is pushed down over the mold; and Fig. 6 is a small sectional view of a part of one of said members.

Referring to Figs. 1 and 2, 6 indicates a bench or support on which the molding is done. 7 and 8 indicate the upper and lower parts of a two-part snap flask, said parts being held in proper register by pins 9 or equivalent devices. After the mold is properly formed according to the usual methods and the pattern removed, it is placed on the run board 10, after which the flask is removed. The mold is as usual made in two parts the plane of division being indicated at 11. The dotted lines 12 indicate the opening in the mold which is to be filled with metal and lines 13 the sprue or opening through which the metal is poured.

In order to protect the mold and hold the sand confined both before and during the pouring operation, the jacket illustrated in

Figs. 3 to 6 is employed. This comprises two duplicate end pieces 14 and 15 and two duplicate side pieces 16 and 17. These pieces will vary in size depending upon the size of the mold. All of the pieces are essentially the same in construction except at the ends where provision is made for fastening them together. The side members have out-turned flanges 18 while the end members have straight flanges 19, said flanges being united by a suitable number of bolts 20. Essentially, the jacket comprises vertical end and side members providing a rectangular box, the interior walls of which are plane surfaces. It thus conforms in shape to the mold shown in Fig. 2, and is open top and bottom whereby it may be pressed down over the mold to confine the same, the internal dimensions of the jacket being such as to make a snug fit. To ensure a snug fit the jacket is made in plan a little smaller than the mold and as it is pushed down over the mold the sharp lower corners 21, Fig. 5, of the jacket which form cutting surfaces thus shave off the excess sand over the entire surface of the vertical faces of the mold from top to bottom. In order to facilitate this shaving operation, each member of the jacket is provided with a large number of outwardly flaring holes 22 having sharp inner edges 23 that scrape or cut the faces of the mold, the excess sand being discharged outwardly due to the outward flare. In addition these holes also permit the gases formed during the casting operation to escape. In order to prevent the members from warping or buckling they are provided with diagonal reinforcing ribs 24.

In operation the workman prepares the mold in the ordinary manner and places it on the run-board 10 and removes the flask. Afterwards, the workman takes a jacket of suitable size and presses it down over the mold, the sharp corners on the lower edge and the edges of the flared holes shaving off the excess sand. The mold is then poured in the usual manner and after the metal is sufficiently cooled, the mold is broken up and the jacket is ready for further use. For small parts the jacket may with advantage be made of aluminum but other metals may be employed. By changing the lengths or widths or both of the parts of the jacket they are readily adapted for various sizes of molds.

I have found in actual practice that these jackets prevent injury to the molds both before and during the pouring operation, and thus the output of a foundry can be increased and there are less losses due to rejections. On account of the fact that the mold is jacketed I find that at least in some cases, a somewhat smaller mold for a given job may be used, than where it is unsupported which of itself is important for obvious reasons.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States is:—

1. A jacket for a sand mold having substantially vertical faces, said jacket comprising a rigid frame which conforms in shape to, and is slightly smaller in plan than the mold, to be jacketed, the edge surfaces on one side of said frame acting from the vertical faces of the mold as cutters to shave off the excess sand as it is pushed over the mold to its final position.

2. A jacket for a mold comprising a rigid open-ended substantially rectangular box-like frame having plane interior surfaces and cutting surfaces along the lower edge and which is adapted to be pushed down over a sand mold to confine the same, said cutting surfaces shaving off the excess sand from the faces of the mold as the frame is moved to its final position.

3. A jacket for a sand mold comprising an open-ended substantially rectangular box-like frame having plane interior walls and cutting surfaces along the lower edge thereof, and means providing other cutting surfaces in and flush with the walls of the

frame, said jacket being adapted to be pushed down over a sand mold to confine the same and in so doing to shave off the excess sand from the faces thereof.

4. A jacket for a mold comprising end and side members which are united at their meeting edges to form an open-ended substantially rectangular box, the interior walls of which are plane surfaces, and which in plan is slightly smaller than the mold, said members being provided with cutting surfaces along their lower edges to remove excess sand from the mold faces while being moved to a final position.

5. A jacket for a sand mold comprising end and side members which are united at their meeting edges to form an open-ended substantially rectangular box, the interior walls of which are plane surfaces and which in plan is slightly smaller than the mold, said members being provided with cutting surfaces along their lower edges and also with a plurality of outwardly-flared openings, said openings providing cutting edges in and flush with the interior walls, which edges cooperate with the cutting surfaces to shave off excess sand from the mold faces from top to bottom while being moved to a final position.

6. A mold jacket of rectangular box-like structure, open top and bottom and comprising vertical end and side members having plane interior surfaces, and being in plan of slightly smaller size than a mold whereby it is adapted to be pushed down over said mold to confine the same, said jacket being provided with cutting surfaces along the bottom edges of the members and a plurality of outwardly-flaring openings extending through said members, said openings serving to vent the jacket and providing cutting edges at their inner ends flush with the interior surfaces of said members.

In witness whereof, I hereunto set my hand this tenth day of September, 1923.

ANTON J. NEMEC.

Certificate of Correction.

It is hereby certified that in Letters Patent No. 1,594,337, granted July 27, 1926, upon the application of Anton J. Nemec, of Cleveland, Ohio, for an improvement in "Jackets for Molds," an error appears in the printed specification requiring correction as follows: Page 2, lines 29 and 30, claim 1, strike out the words "from the vertical faces of the mold" and insert the same to follow after the word "sand," line 31, same claim; and that the said Letters Patent should be read with this correction therein that the same may conform to the record of the case in the Patent Office.

Signed and sealed this 14th day of September, A. D. 1926.

[SEAL.]

M. J. MOORE,
Acting Commissioner of Patents.
